United States Patent Office.

A. D. SMITH AND E. STOW, OF TOWNSEND STATION, OHIO.

Letters Patent No. 75,994, dated March 24, 1868.

IMPROVEMENT IN FENCES.

The Schedule referred to in these Letters Patent and making part of the same.

TO ALL WHOM IT MAY CONCERN:

Be it known that we, A. D. SMITH and E. STOW, of Townsend Station, in the county of Huron, and State of Ohio, have invented certain new and useful Improvements in Farm-Fences; and we do hereby declare that the following is a full and complete description of the same, reference being had to the accompanying drawings, making a part of this specification, in which—

Figure 1 is a front view.

Figure 2 is a top view.

Figure 3 is a detached section.

Like letters of reference refer to like parts in the views.

In the drawings, A represents the base or ground, in which are secured the posts B. C C are the pickets, near the top and bottom of which are inserted the loops or hooks a a.

These pickets are connected together and supported in the following manner: Secured to the posts are the wires D. There may be two or more, as desired; these wires being secured to the posts by means of the staples or hooks a. The wires, when secured to the posts, are indented, as shown, from the points a to a', to receive the pickets, forming a shoulder, as in fig. 2, on each side of the said pickets.

Fig. 3 is a detached view of the wire, which is indented as stated, the pickets resting between the shoulders a and a'. The object of making the wire in this way, and indenting it to receive the pickets, is to support and keep the pickets in place, preventing them from moving or being pushed to either side, and also supporting them by means of the staples by which the wires are secured, which, with the method of securing the pickets to the said wires by means of the staple, forms a strong support, and prevents the pickets from moving out of place.

We are aware that pickets have been and still are secured to a wire or wires by means of hooks and staples, said staples being driven into the picket, hard down upon the wire, but we do not claim the manner of attaching the picket to the wire; but

What we claim as our improvement, and desire to secure by Letters Patent, is—

A fence, constructed with an indented wire or wires, in combination with the hooks a and pickets C, as and for the purpose specified.

A. D. SMITH,
E. STOW.
